LOUIS L. ARNOLD, OF NEW YORK, N. Y.

Design No. 2,627, dated April 23, 1867.

DESIGN FOR A TRADE MARK.

The Schedule referred to in these Letters Patent and making part of the same.

TO ALL WHOM IT MAY CONCERN:

Be it known that I, LOUIS L. ARNOLD, of the city, county, and State of New York, have originated a new Design for a Trade Mark, the same to be used as a seal or stamp on the envelopes, vials, bottles, jars, boxes, &c., of certain medicines prepared after recipes which have to be held secret, consequently can be protected against fraudulent imitation, &c., only by the means of a trade mark affixed to said envelopes, bottles, &c., in a manner so as to be cancelled or destroyed by opening the covering, wrapper, or cork for using the said medicine.

The accompanying drawing will clearly show my design, consisting of an outer band or strip (to bear the name of the medicine) encircling the inner disk, upon which appears a heraldic shield bearing the emblems of my family—a baronial crown of gold in the centre, surrounded by three spread black eagles flying towards said crown. I intend to use said trade mark as a seal, as a stamp, and finally, in form of lithographic fancy engraving, in which latter style the outer strip would be gold, the inner disk purple, the shield silver, and the heraldic figures as described above.

What I claim as my invention, and desire to secure by Letters Patent, is—
The design for a trade mark herein set forth and shown.
